UNITED STATES PATENT OFFICE.

LEVI J. ODELL, OF LOS ANGELES, CALIFORNIA.

BLADE GRINDING AND SHARPENING MACHINE.

1,111,815.

Specification of Letters Patent. Patented Sept. 22, 1914.

Application filed December 18, 1912. Serial No. 737,610.

To all whom it may concern:

Be it known that I, Levi J. ODELL, a citizen of the United States, residing at Los Angeles, in the county of Los Angeles and State of California, have invented new and useful Improvements in Blade Grinding and Sharpening Machines, of which the following is a specification.

This invention relates to improvements in machines for grinding and sharpening blades adapted for various purposes, as safety razor blades, and the principal object is to provide a machine that will automatically grind and sharpen the blades in one continuous operation.

It is also an object to provide means to grasp the blade and support the latter between a pair of abrading rollers so that the blade is effectively ground and sharpened on both of its faces.

It is a further object to provide a grinding and sharpening machine in which the blade is oscillated between a pair of rollers having abrading surfaces formed of successive sections, whereby the blade reciprocated transversely to these abrading sections is successively ground, sharpened and honed.

In the drawings accompanying this specification and forming therewith the application for Letters Patent: Figure 1 is a side elevation of the complete machine viewed from the blade supporting side. Fig. 2 shows a section through the table top longitudinally, showing the abrading rolls in elevation viewed from the same side as in Fig. 1. Fig. 3 is a plan view of the machine showing the blade holder in position, and showing the blade holder with a contained blade in contact with the portion of the roll having the grinding surface. Fig. 4 is a section on the line 4-4 of Fig. 3 viewed in the direction indicated by the arrows, the bottom portion of the machine being shown in end elevation. Fig. 5 is a plan view on an enlarged scale of the blade holder, holding a blade used in the looms of carpet manufacturers. Fig. 6 is a side elevation of the holder, also on an enlarged scale viewed from the side showing the blade setting gage. Fig. 7 is an end view of the blade supporting holder showing the threaded socket.

In the drawings numerals are used to indicate the component parts in the different views, 10 designating the table top, preferably of cast metal and supported on the

end frames 11, which consist of the vertical legs having the shaft bearing support 12 intermediate of the top of the table and its feet, together with the lower shelf 14, which securely braces the whole and forms a support on which is preferably mounted the driving motor 15, shown as an electric motor of the common type provided with the driving pulley 16.

Mounted on the table is the bracket 17 provided with the base 18, which rests upon the table and is secured by suitable bolts 19. This bracket 17 forms the bearings and support for the abrading rolls 20 and 21 mounted on the shafts 22 and 23, respectively. The bearings and the brackets for these shafts are preferably vertically disposed and in the same vertical plane, one shaft being placed immediately above the other. The upper shaft 22, is preferably longer than the lower shaft and its end oppositely disposed from that on which the abrading roll 20 is secured, extends outwardly beyond the shaft 23 and is provided with the pulley 24, which occupies such a position, that a belt 25 carried over this pulley will not interfere with the pulley 26 mounted on the end of the shaft 23 in the same relative position, or the belt 27 carried thereby. To properly lubricate these bearings a spindle 28 is secured on the frame extending outwardly therefrom, and oppositely disposed from the blade supporting brackets, on the outer end of which is secured the grease-cup 29 provided with a plurality of connecting pipes 30, which extend to the four bearing sections or bushings for the two shafts 22 and 23. This grease-cup is preferably provided with a threaded cap by which pressure is applied to force the grease through these pipes and their unions 31 to the bearing surfaces in the frame 17.

The abrading rolls are preferably built up of a number of sections usually and preferably annular in form mounted upon the free ends of the shafts 22 and 23, the various sections 127, 128, and 129 being held securely in position by means of the washer 130, and clamped in position by means of the nut 131 which is secured to the threaded end 32 of the shaft. An annular flange 33 is formed on the shafts for taking up and forming a thrust for the action of the nut 131.

The blade supporting and moving mechanism is preferably supported on two indi-

vidual frames or standards 34 and 35, each of which is provided with suitable flanged base secured by bolts 36 to the table so that the shaft mounted therein is parallel to and in a horizontal line or plane intermediate of the two shafts 22 and 23. Each one of these standards is provided with suitable bearings 37 which carry the shaft 38 revolvably mounted therein, suitable oil or grease-cups 39 being provided by which the bearings are properly lubricated. The frame 34 or that placed nearest to the frame 17 is provided with an elongated bearing 40 in which is mounted the short shaft 41, a suitable grease-cup 42 being provided by which this bearing is lubricated. On the end of this shaft adjacent the pulleys for the abrading rolls the pulley 43 is secured by means of a suitable screw 44, and is also adapted to carry a belt 45. The inner end of the shaft 41 is provided with a disk-plate 46 slotted transversely and diametrically at 47 to accommodate the slide 48 mounted therein, provided with a stud 49 extending outwardly parallel with the shaft and having the sleeve 50 mounted thereon and secured in position by means of the nut 51 on the outer threaded end of the stud. This sleeve 50 is provided with a short stud or rod 52 which is also threaded on its outer and reduced end passing through a bore in an annular plate 53 forming one end of the connecting box 54. A nut 55 secured to the threaded end locks the stud in this box and allows the same to be swiveled thereon, the opposite annular plate of the box having a centrally disposed threaded bore in which is threaded the pitman connection 57. This pitman is provided with an eye at its opposite end by which it is pivotally connected in the lugs 58 projecting from the oscillating sleeve 59 which sleeve is pivotally mounted on the shaft 38.

The oscillating sleeve 59 is provided with bearings at its oppositely disposed ends 60, which abut against the inner faces of the bearings 37 on the two standards 34 and 35 so that no lateral movement is possible. This sleeve is cut away on the oppositely disposed side from that bearing the lugs 58 and secured thereto is a longitudinally slotted block 61 forming a guideway, the inner vertical face of which in contact with the semi-circular portion of the sleeve is preferably in a plane to one side of the vertical axial plane of the shaft, this guideway being secured to the sleeve in any well known manner and extending approximately the full length of the sleeve, with the exception of the bearings. The upper face of the sleeve intermediate of the bearings and the cut away portion is flattened to form a bearing surface for the oppositely disposed slotted block 62 forming a guide-way, which is provided with a web, which engages on the flattened surface previously mentioned and

provides the opposite or upper guide for the block 63 secured to the inner end of the blade holder 64, the interval between the respective flanges on the two guide blocks 61 and 62 being such as to include the thickness of the blade holder 64. 70

The upper block 62 of the guide-way is of less length than its oppositely disposed and coöperating guide-block 61, forming an interval at either end into which the block 63 can be introduced or removed, this block having a section formed with a semi-circular recess 65, a portion of this being threaded at 66 to agree with the threads 67 cut on the shaft 38, this thread being preferably extended a slight distance beyond either end of the guide block 62. The outer end of the shaft 38 carried through the bearing in the standard 35 is provided with a pulley 68, which is in line with the pulley 69 on the intermediate driving shaft 70. The blade holder 64 is shown as a flattened rectangular structure projecting outwardly and oppositely from the face of the block 63 opposite the recessed semi-circular face having the threads cut thereon, the construction being such that the block can slide within the guide-way and be supported therein. 80 90

The blade holding portion 64 is provided with a groove extending inwardly from its outer edge into which the two clamping jaws 71 and 72 are secured by means of the screw or pin 73. A wing bolt 74 is carried through a bore in the upper clamp arm 71 and engages a threaded bore in the lower blade clamping jaw 72, by which a blade as 75 may be clamped between the jaws securely and accurately. 95

To provide for the accurate adjustment of the blade or blank 75, of the pile cutting type shown, the upper plate is cut away at the point 76 and a finger 77 formed on the extreme edge of the clamping jaw which extends over the blank as shown in Fig. 5. 105 110

Mounted on the edge of the clamping jaws, opposite the edge having the cut-away portion, is a gage plate 78 slidably mounted in a guide-way 79 secured to the lower clamping jaw 72. The guide-way 79 is provided with a slot through which the gage operating handle 80 projects, a spring 81 being provided and connected to the inner end of the gage and secured to the block 63 in a suitable manner so that the gage is normally held to the inner limit allowed the handle by the slot in the guide-way. The function of the gage 78 is to facilitate the proper positioning of the blade 75 between the clamping jaws 71 and 72, the gage being pushed 115 120 125 outward to its limit, as indicated in dotted lines in Fig. 5, to form a stop against which one edge of the blade is fitted when adjusting it between the clamping jaws. When the blade 75 is properly positioned the gage 130

78 is retracted to its normal position by means of the spring 81. In Fig. 6 the blank 75 is shown in dotted lines, and the shape of the point after grinding on both faces is indicated by full lines.

10 A suitable handle 84 is secured in the upper face of the blade holder by which the latter is handled and inserted in position or removed from the guide-way after the completion of the grinding and sharpening of the blank.

As previously stated, the device is preferably driven by an electric motor 15, its pulley 16 carrying a suitable belt which is carried over the pulley 82 mounted on the shaft 83, whose bearings rest upon the cross arm 12, this shaft being parallel with and oppositely disposed to the shaft 70 also mounted on the cross arm 12 in suitable bearings. From the pulley 84 securely mounted on the shaft 83 a belt 85 is carried over the large pulley 86 mounted on the shaft 70 adjoining which pulley is the smaller pulley 87 over which is carried the belt 45 connecting with the pulley 43 on the shaft 41 by which a rocking action is given to the blank carried in the blade holder. The direction of the various shafts and rolls, together with their belts is indicated by the arrows, the belt 45 being crossed as is also the belt connecting the pulley 69 mounted on the shaft 70 to the pulley 68 on the threaded shaft 38. A suitable double grooved pulley 88 is mounted on the shaft 83 in line with the pulleys 24 and 26 to carry the belts 25 and 27, respectively, the belt 25 being crossed so that the abrading roll 20 mounted thereon is revolved in a reverse direction to the roll 21, so that the abrading surfaces are passed by the edge of the blank to form the blade and not against the edge to be ground and sharpened.

In the operation of the device the blank is clamped in the clamping jaws as previously described, while the blade holder and its block are removed from in contact with the guide-ways or the driving screw threads, and the block is brought into position at the point 90 and dropped into the groove in the lower guide-way 61. The shaft 38 being in motion and revolving toward the operator, or away from the grinding rolls the first thread engages with the threads cut in the semi-circular recess in the block 63 and propels the block to the left as indicated by the arrows until it reaches the point 92 where the block is only in engagement with the lower guide-way and the engagement with the screw thread has been lost on the shaft 38, the block and clamping jaws attached thereto remaining at rest until such time as it is removed. While traveling along this path the sleeve is coincidentally rocked or oscillated to throw the blade in contact with the successive surfaces of the abrading rolls.

connecting first with the coarser grinding section 127, next in succession the finer surface of the section 128, and finally the hone surface 129 on the extreme free ends of the abrading rolls.

Suitable openings are provided in the table top 10, through which the belts are carried and to receive the bolts securing the flanged bearing standards to the table, the table top being preferably provided with a downwardly extending flanged edge to add stiffness to the structure. As is well understood by the use of suitable blade holder any type of wafer blades as razor blades can be ground and sharpened in this machine.

What I claim is:

1. In a machine for grinding and sharpening flat blades, a pair of spaced parallel abrading rolls, means for rotating said rolls in unison in opposite directions, a worm-shaft arranged parallel with said rolls, a slotted sleeve rockably mounted on said shaft, longitudinal guide-ways on said sleeve, a block adapted to be inserted through the slot in the sleeve and engaged with the worm-shaft having an extension projecting through the guide-way, blade clamping jaws on said extension, and means for simultaneously rotating the worm-shaft and rocking the sleeve thereon, whereby a blade carried by the clamping jaws will be caused to oscillate between the abrading rolls and at the same time be advanced from one end of the rolls to the other.

2. In a blade grinding and sharpening machine, a worm-shaft, a sleeve rockably mounted thereon having a longitudinal slot, a block having a threaded semi-cylindrical face adapted to be engaged by the worm-shaft, means on said block for carrying blades to be sharpened, means for guiding said block longitudinally of the sleeve, and means for rotating the shaft and rocking the sleeve simultaneously, whereby the block will be advanced by the worm-shaft to give the blade-carrier a combined oscillating and reciprocating movement.

reciprocating movement.

3. In a blade sharpening and grinding machine, a shaft having worm threads throughout a portion of its length, a sleeve 115 rockably mounted on said shaft formed with a longitudinal guide slot and having peripheral extending openings adjacent its ends opposite the unthreaded portions of the shaft, a movable block formed with a semi-cylindrical threaded face and having a projection adapted to be slidably engaged with the guide slot in the sleeve, blade-carrying means on said projection, said block adapted to be in engagement with the threaded shaft through one of the openings in the sleeve and removed from the other opening in the sleeve after being advanced by the worm-shaft, means for rotating said worm-shaft to advance the block, and means 120 125 130

- for rocking the sleeve, whereby the blade-carrying means will be given an oscillating movement while it is being advanced with the block.
5. In a blade grinding and sharpening machine having a pair of spaced parallel abrading rolls, a blade holder, a block on which said blade holder is mounted, a worm-shaft, means on said block for detachably connecting it to said worm-shaft, an oscillating member having a guide for slidably engaging said block, means for rotating the worm-shaft to advance the block, and means for actuating said oscillating member, whereby the block will be given a rocking movement in conjunction with its advancing movement to move a blade on the blade carrying means in and out of contact with the abrading rolls while the blade is being advanced longitudinally thereof.
10. In a machine for sharpening and grinding flat blades, a pair of spaced parallel cylindrical abrading rolls, a worm-shaft arranged parallel to said rolls, a block adapted to be advanced by the latter in one direction, blade-clamping jaws carried by said block arranged to dispose a blade intermediate the abrasive rolls, and means for supporting and guiding said block adapted to be rocked to move the blade longitudinally in and out of contact with the abrading rolls while said block is being advanced by the worm-shaft.
15. In a machine for grinding and sharpening flat blades having a pair of parallel rolls formed with different grades of abrasive surfaces thereon, a worm-shaft arranged parallel with said rolls, a block formed with a semi-cylindrical channel having worm teeth to engage the worm-shaft, blade-clamping jaws on said block, means for detachably holding the block in engagement with the worm-shaft and guiding it thereon adapted to be rocked to oscillate the block, means for rotating the worm-shaft to advance the block to move the blade successively from one grade of abrading surfaces on the roll to the other grades, and means for oscillating the block holding and guiding means, whereby the blade will be moved in and out of contact with the abrading surfaces to grind its opposite sides at one edge.
20. In a sharpening and grinding machine having a pair of spaced cylindrical abrading rolls, a portable block, blade holding means on said block, a worm-shaft paralleling the abrading rolls, means for detachably engaging the block with said worm-shaft, whereby rotation of the latter will advance the block in one direction to move a blade in the blade holder longitudinally of the rolls, means whereby the block may be fed to the worm-shaft and engaged thereby at the beginning of its stroke and automatically disengaged therefrom at the end of its stroke, and means for oscillating the block to move the blade in and out of contact with the abrading rolls during its advancement.
25. In witness that I claim the foregoing I have hereunto subscribed my name this 12th day of December, 1912.
